UNITED STATES PATENT OFFICE.

OTIS H. FOLSON, OF WATERVILLE, MAINE.

PAPER-STOCK MACHINE.

1,236,281.

Specification of Letters Patent. Patented Aug. 7, 1917.

Application filed December 20, 1916. Serial No. 138,080.

To all whom it may concern:

Be it known that I, OTIS H. FOLSON, a citizen of the United States, residing at Waterville, in the county of Kennebec and 5 State of Maine, have invented new and useful Improvement in Paper-Stock Machines, of which the following is a specification.

The invention relates to a paper stock machine.

10 The primary object of the invention is the provision of a machine of this character wherein the same is operated with minimum power and the parts are free from wear and the interior thereof is readily accessible on the raising of the screen plate tank from the vat.

Another object of the invention is the provision of a machine of this character wherein the screen will effect a saving in 20 the screening of stock and the stroke of the screen is readily adjustable to allow proper action for different grades of stock.

A further object of the invention is the provision of a machine of this character 25 wherein the paper stock will be acted upon through the medium of a suction and compression effect through the action of rocking mechanism in a liquid sealed chamber so that the stock will be thoroughly screened 30 prior to its discharge from the machine.

A still further object of the invention is the provision of a machine of this character which is simple in construction, thoroughly reliable and efficient in operation, strong, 35 durable and inexpensive in manufacture.

Other objects will be in part obvious and in part hereinafter set forth.

The invention accordingly consists in the features of construction, combination of elements and arrangement of parts which will 40 be exemplified in the construction hereinafter described, and the scope of the application of which will be indicated in the appended claims.

45 In the accompanying drawings:

Figure 1 is a side elevation of a machine constructed in accordance with the invention;

Fig. 2 is an end elevation thereof;

50 Fig. 3 is a top plan view;

Fig. 4 is a vertical longitudinal sectional view through the machine;

Fig. 5 is a vertical transverse sectional view through the machine.

55 Similar reference characters indicate cor-

responding parts throughout the several views of the drawings.

Referring to the drawings in detail, A designates generally the supporting frame which includes the spaced vertical uprights 10, upper and lower side beams 11 and 12 respectively, and a cross end piece 13, which latter is fixed to one pair of the uprights 10 at the upper ends thereof, the beams being secured to the uprights 10 in any suitable manner, and connected to the cross end piece 13 and the uprights supporting the same are hinges 14 which swingingly support a screen frame 15 in which is arranged a reticulated plate 16 forming a screen, while 60 fixed to the walls of the frame 15 below the screen 16 is a hanger frame 17 supporting a shell 18 which depends therefrom and has arranged medially therein, a partition 19 which is fixed in a cross piece 20 in the hanger frame 17, the partition being 65 designed to divide the shell 18 into chambers 21 which form compression and suction chambers for a purpose presently described.

Journaled centrally in the upper beams 11 is a rocking shaft 22 supporting a rocking tank 23 providing a liquid vat into which depends the shell 18, and interiorly of this vat are fixed displacement boxes 24 which work within the respective chambers 70 21 and serve to alternately effect a suction and compression on the rocking of the vat in a manner and for a purpose presently described.

Secured to the bottom of the tank constituting the vat 23 are substantially V-shaped hangers 25 constructed to receive the cross pins 26 of an eccentric throw rod 27 which is connected to an eccentric pin 28 adjustably mounted in a wheel 29 journaled in a standard 30 supported upon a rest 31 therefor fixed to the lower beams 12 of the support. Also mounted upon the lower beams 12 are rests 32 for a motor 33 preferably of the electric type, which operates 80 a drive belt 34 trained over the wheel 29 so that motion from the motor will be imparted to the said wheel 29 and its motion will be converted from rotary into reciprocating movement by the eccentric rod 27 85 which rocks the tank 23 for a purpose presently described.

Fixed to the upper beams 11 near opposite ends thereof are platforms 35 upon which are mounted expansion springs 36, the same 90

acting against the bottom of the tank 23 and serving as shock absorbers during the operation of the machine.

Leading from one side of the tank and 5 communicating therewith is a delivery spout 37 for the discharge of the screened paper stock from the vat while the machine is in action.

In the operation of the machine, initially, 10 water is introduced through the screen frame 15 and plate 16 for the filling of the vat 23 a predetermined height to form a liquid seal between the shells 16 and the said vat and thereafter the paper stock is fed into 15 the screen frame 15. When the motor 33 has been started the vat 23 is rocked on the shaft 22 and by the rise and fall of the displacement boxes 24 an alternate suction and 20 compression will be effected in the chambers 21 in the shell 18, thereby drawing the stock through the perforations in the screen plate 16 into one chamber 21 and forcing under pressure the stock within the vat 23 upwardly through the screen plate 16 25 through the other chamber 21, and this operation is continuous, as will be apparent. It will be obvious that when the vat is in motion the stock is being drawn down through the screen at one end, while at the 30 opposite end it is being cleaned, and this allows a continuous stream of screen stock to flow out through the spout at the side of the machine. Fixed exteriorly about the shell 18 is a fender 38, the latter being station- 35 arily mounted upon the frame 17, while carried by said shell 18 and surrounding the same is a fender 39, which fenders coöperate with each other to prevent the splashing of the stock from the vat during the operation 40 of the machine.

From the foregoing description, taken in connection with the accompanying drawings, the construction and operation of the herein described paper stock machine will 45 be readily apparent and, therefore, a more extended explanation has been omitted.

Having thus described my invention, I claim:

1. A paper stock machine comprising a 50 rocking vat, a screening frame above said

vat, a shell depending from the screening frame within the vat and forming compression and suction chambers, and means within the vat and working within the chambers to effect alternate suction and compression 55 therein.

2. A paper stock machine comprising a rocking vat, a screening frame above said vat, a shell depending from the screening frame within the vat and forming compression and suction chambers, means within the vat and working within the chambers to effect alternate suction and compression 60 therein, and means for rocking the vat.

3. A paper stock machine comprising a 65 rocking vat, a screening frame above said vat, a shell depending from the screening frame within the vat and forming compression and suction chambers, means within the vat and working within the chambers to 70 effect alternate suction and compression therein, means for rocking the vat, and shock absorbers acting upon the vat.

4. A paper stock machine comprising a 75 rocking vat, a screening frame above said vat, a shell depending from the screening frame within the vat and forming compression and suction chambers, means within the vat and working within the chambers to effect alternate suction and compression 80 therein, means for rocking the vat, shock absorbers acting upon the vat, and fenders on the vat and shell to coöperate with each other for preventing splashing of the contents of said vat.

5. A paper stock machine comprising a 85 rocking vat, a screening frame above said vat, a shell depending from the screening frame within the vat and forming compression and suction chambers, means within the 90 vat and working within the chambers to effect alternate suction and compression therein, means for rocking the vat, shock absorbers acting upon the vat, fenders on the vat and shell to coöperate with each other 95 for preventing splashing of the contents of said vat, and a delivery spout leading from the vat.

In testimony whereof I affix my signature.
OTIS H. FOLSOM.
